UNITED STATES PATENT OFFICE

HENRY W. DEVLIN, OF DENVER, COLORADO

KEY CUTTING MACHINE

Application filed August 22, 1930. Serial No. 477,123.

This invention pertains to new and useful improvements in machines for cutting keys.

The principal object of this invention is to provide a machine for duplicating keys of the type generally used in automobile locks, wherein the keys are issued under a secret code number.

Important objects and the advantages of invention will readily become apparent to the reader of the following specification.

In the drawings:—

Figure 1 represents a side elevational view of the novel machine.

Fig. 2 represents a top plan view of the machine.

Fig. 3 represents a fragmentary detail sectional view of the machine.

Fig. 4 represents a fragmentary detail sectional view.

Fig. 5 represents a fragmentary detail sectional view of the key gauge.

Fig. 6 represents a fragmentary detail sectional view of the blank supporting sleeve.

Referring to the drawings wherein like numerals designate like parts, it can be seen that the novel machine includes a supporting body 5 which is provided with a depending portion 6 carrying the screw clamp member 8 and associated clamp plates 7. The feed screw is operable by the handle 9, as clearly shown in Fig. 1.

A bearing 10 on the body has the shaft of the notch cutting wheel 11 journaled therethrough and to which the crank 12 is secured at one end by the set screw 13. A barrel 14 in parallel relation to the bearing 10 and also located on the body 5 slidably receives the cylinder 15, to which the cylindrical gauge head 16 is secured by the bolt 17.

Longitudinally at spaced intervals the head 16 is provided with circumferentially extending grooves 18 within which the dog 19 is selectively engaged, the said dog being urged against the head 16 by the spring 20.

At the opposite end of the cylindrical

member 15 from the head 16 is a block 21. This block has a dove-tailed groove therein for slidably receiving the plate 22 which has its longitudinal edge portions beveled for engagement in the said dove-tailed groove. 50 The plate 22 has nuts 23 fixed thereto through which the feed screw 24 passes. This screw 24 is provided with a knob 25 at one end and is provided with a grooved extension 26 at its opposite end which engages within a pocket 27 in the block 21.

A set screw 28 is engageable in a bore in the block 21 to engage at its inner end into the grooved extension 26. The plate 22 is provided with a shoulder 29 and between this shoulder 29 and the inner end of the plate 22, a movable clamp plate 30 is provided, the same being provided with a reduced portion 31 and an inwardly disposed lip 32 which can engage in the usual slot in the key blank. 65

Disposed through registering openings in the plate 22 and plate 30 is the bolt 33 on which the winged nut 34 is engageable whereby the plate 30 can be clamped against the plate 22 to secure a key blank in the position shown substantially in Fig. 2. 70

An arm 35 is pivotally mounted as at 36 upon the plate 22 and is provided with a yoke 37 at one end for receiving the upstanding pin 38 on the block 21. A scale 39 is arranged 75 on the block 21 in the path of the opposite end of the arm 35 from its yoked end, so that the depth to which the notch is to be cut, can be regulated accurately.

It can thus be seen that by shifting the cylinder 15 in the proper direction, the key blank supporting means can be regulated to position the key blank properly with respect to the cutting wheel 11. The blank holding means will be retained against self-adjusting 80 by means of the dog 19 engaging in the selected groove 18 of the head 16. As the notch is being formed in the blank, the knob 25 can be rotated to permit the cutting of the notch to the desired depth. 90

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

1. A key cutting machine comprising a supporting body, a shaft journaled therein, a cutter on one end of the shaft, a tubular part formed on the body and paralleling the shaft, a member slidably arranged in the tubular part and having a plurality of notches in one end thereof, a spring-pressed dog for engaging any one of the notches for holding the sliding member in adjusted position, a plate supporting member at the opposite end of the sliding member, a transversely arranged sliding plate on said supporting member, means for holding a key on the plate, a screw shaft rotatably supported on the plate supporting member and engaging a threaded part on the plate for moving the plate towards and away from the cutter to bring the key against the cutter when the plate is moved towards the same, and means for rotating the shaft.
2. A key cutting machine comprising a supporting body, a shaft journaled therein, a cutter on one end of the shaft, a tubular part formed on the body and paralleling the shaft, a member slidably arranged in the tubular part and having a plurality of notches in one end thereof, a spring-pressed dog for engaging any one of the notches for holding the sliding member in adjusted position, a plate supporting member at the opposite end of the sliding member, a transversely arranged sliding plate on said supporting member, means for holding a key on the plate, a screw shaft rotatably supported on the plate supporting member and engaging a threaded part on the plate for moving the plate towards and away from the cutter to bring the key against the cutter when the plate is moved towards the same, means for rotating the shaft, and gauge means for indicating the amount of movement of the sliding plate.
3. A key cutting machine comprising a supporting body, a shaft journaled therein, a cutter on one end of the shaft, a tubular part formed on the body and paralleling the shaft, a member slidably arranged in the tubular part and having a plurality of notches in one end thereof, a spring-pressed dog for engaging any one of the notches for holding the sliding member in adjusted position, a plate supporting member at the opposite end of the sliding member, a transversely arranged sliding plate on said supporting member, means for holding a key on the plate, a screw shaft rotatably supported on the plate supporting member and engaging a threaded part on the plate for moving

the plate towards and away from the cutter to bring the key against the cutter when the plate is moved towards the same, means for rotating the shaft, gauge means for indicating the amount of movement of the sliding plate, said means comprising a lever pivoted to the plate, a scale on the plate supporting member with which one end of the lever cooperates, the opposite end of the lever being forked and a pin on the plate supporting member extending into the space formed by the prongs of the fork.

In testimony whereof I affix my signature.

HENRY W. DEVLIN.
